UNITED STATES PATENT OFFICE.

WILLIAM E. SMITH, OF MILLTOWN, NEW JERSEY, ASSIGNEE TO KILBOURN MANUFACTURING CORPORATION, OF NEW BRUNSWICK, NEW JERSEY, A CORPORATION OF NEW JERSEY.

CIRCULAR-KNITTING MACHINE.

1,169,436.

Specification of Letters Patent. Patented Jan. 25, 1916.

Application filed June 2, 1914. Serial No. 342,398.

To all whom it may concern:

Be it known that I, WILLIAM E. SMITH, a citizen of the United States, residing at Milltown, in the county of Middlesex and State of New Jersey, have invented certain new and useful Improvements in Circular-Knitting Machines; and I do hereby declare the following to be a full, clear, and exact description of the invention, such as will enable others skilled in the art to which it appertains to make and use the same.

My invention consists in the novel features hereinafter fully described, with reference to the accompanying drawings, which illustrate one embodiment of my invention selected by me for the purpose of illustrating the same, and the said invention is fully disclosed in the following description and claims.

Referring to the accompanying drawings, Figure 1 represents a sectional view of a portion of a knitting machine which I conveniently employ for carrying my invention into effect. Fig. 2 is a diagrammatic perspective view illustrating the operation of the needles knitting the rear portion of the stocking and the various thread guides which I prefer to employ for supplying the main knitting thread and reinforcing thread.

Fig. 3 is a partial view representing the interior of the upper knitting cam of the knitting machine shown in Fig. 1 having my present invention applied thereto. Fig. 4 is a vertical sectional view of the cam showing two needles in operative relation therewith. Fig. 5 is a diagrammatic representation of a stocking with the high spliced portion knit according to my invention.

Fig. 6 is a diagrammatic representation of Fig. 5. Fig. 7 is a partial diagrammatic view representing a modified form of stocking knit in accordance with my invention.

The object of my invention is to provide means in a seamless stocking knitter or machine for knitting seamless stockings with narrowed and widened heel and toe pockets, for forming a reinforced portion on the back of the stocking above the heel of less width than the heel, or in other words, having a less number of stitches in each course reinforced than the number of stitches employed in knitting the widest courses of the heel pocket. It is customary in knitting seamless stockings to introduce the reinforce-

ing thread in a number of courses above the heel, at the rear of the stocking leg in order to thicken that portion of the stocking to resist wear from the counter of a low shoe or the seam of a high shoe where the upper joins the counter, and it has been usual to carry the reinforcing thread into the same number of stitches in each course as are used in forming the first course of the heel pocket. This is somewhat objectionable especially where the reinforced courses extend a considerable distance above the heel pocket as the thickened portion which is termed the "high splice" extends around toward the ankle joint on each side of the stocking and shows very distinctly when the stocking is worn with low shoes, pumps, or slippers. This is especially the case with fine or more or less transparent goods in which the heavy high splice stands out in marked contrast to the more transparent portions of the leg of the stocking. In carrying out my invention therefore, I propose to knit all the courses of the high splice or the majority of such courses with a much smaller number of reinforced stitches in each course than the entire number of stitches in the first course of the heel pocket, thereby materially narrowing the high spliced portion of the stocking, and confining it to the rear portion thereof so that it projects only a little way at each side and is inconspicuous when worn while affording sufficient reinforcement at the part of the stocking directly exposed to wear from the upper edge of the counter or the seam between the counter and upper.

In carrying out my invention I prefer to employ a seamless stocking knitter of the type known as the Kilbourn knitting machine, and such a machine as is illustrated, for example, in U. S. Letters Patent #1,087,954, granted to E. E. Kilbourn, W. E. Smith, and I. W. Kilbourn, under date of Feb. 24, 1914. In this type of stocking knitter the needles of the circular series are operated by two separate cams carried by separate cam cylinders, disposed one above the other in the machine, the portion of the needles which knit the front portion of the leg and top portion of the foot of the stocking, and which I will indicate by the letter α , being provided with nubs to operatively engage the lower cam cylinder, and the needles which knit the rear part of the leg, β .

the heel and toe pockets, and the sole portion of the foot, being provided with nibs operatively engaging the upper cam cylinder.

5 In Fig. 1 of the drawing, which represents a sectional view of the knitting machine head, 1 represents the knitting cylinder provided at its upper end with a nosing 2 carrying the usual horizontal reciprocating sinkers 3, operatively engaged by a sinker actuating cam ring 4. 5 represents the upper cam cylinder and 6 represents the lower cam cylinder, all of these parts being of the substantial form and construction illustrated 15 in the patent before referred to.

The needles which knit the rear portion of the stocking, the heel and toe pockets, and the sole portion of the foot, may be said to be divided into two classes, to wit, a centrally disposed portion which I will indicate by the reference letter x' all of which knit at every reciprocation of the upper cam cylinder during reciprocating work, and are not affected by the pickers, and a series of 20 needles at each side of the needles x' , which I will indicate by the reference letter x^2 which are successively thrown out of operation during narrowing and into operation during widening, while making the heel and 25 toe pockets, and which for convenience of reference I term the fashioning needles. A portion of the fashioning needles x^2 and the centrally disposed needles x' between the same are indicated diagrammatically in 30 Fig. 2.

In carrying out my present invention I provide the centrally disposed needles x' , which are not affected by the pickers, with the usual or long nibs, indicated at x^3 (see 40 Fig. 4), while the fashioning needles are provided with a shorter nib x^4 (Fig. 4). The upper cam cylinder which actuates the needles knitting the rear half of the stocking fabric is provided with a leading cam ridge 5^a in advance of the knitting cam 5^b, which is of such width that it will actuate the long nib needles, but will not actuate the short nib needles. During the knitting 45 of the circular work it will be understood that both cam cylinders are rotated simultaneously, the lower cam cylinder operating the needles knitting the front portion of the leg, and the upper cam cylinder actuating the needles for the back portion of the leg, and as the upper cam moves around, the leading cam 5^a will engage the long nibs x^3 of the needles x' and raise them into a higher plane than the fashioning needles at either side, which are provided with the 55 short nibs, so as to enable the needles x' to receive a reinforcing thread indicated at 10^a, which will be fed thereto by an auxiliary thread guide 10, and which will not be fed to any of the other needles not so raised. 60 The main knitting thread indicated at 11^a

will be fed in the usual manner by the main thread guide 11 and will be taken by the needles x^2 as well as the needles x' so that the reinforced fabric forming the high splice above the heel is limited to the number of 70 needles raised by the leading cam 5^a. I prefer to provide all the needles x' with the long nib x^3 , as indicated in Fig. 2, but it is obvious that a number of these needles x' less than the entire number between the two 75 sets of fashioning needles x^2 might be provided with the long nibs and the remaining needles x' might be provided with the short nibs so as not to be actuated by the leading cam 5^a which would reduce the number of 80 stitches reinforced in each course still further, as indicated in Fig. 7, in which the dotted line b^3 indicates the width which the high splice would have if all the needles x' were provided with the long nib, and b^4 85 represents the high spliced portion knit by a lesser number of the needles x' which are provided with the long nibs as before described, and it is obvious therefore that with this arrangement I can vary the width 90 of the high splice portion considerably if found desirable.

It is obvious that after the thread guide 10 has fed the reinforcing thread 10^a to the needles x' having the long nibs and held in elevated position, as shown in Fig. 2, the reinforcing thread will float across the cylinder, as indicated by the dotted line in Fig. 6 and the float threads will be severed after the stocking is knit, in the usual manner adjacent to each side of the stocking. 100

In Fig. 5 I have illustrated a stocking knit in the manner described, in which a represents the leg of the stocking, b represents the narrow high spliced portion, c 105 the heel pocket, d the top of the foot, e the sole of the foot, and f the toe pocket, the portions of the stocking not particularly described herein being knit in the well known manner. 110

In some instances I may desire to knit a few courses of reinforced fabric immediately above the heel of the full width of the heel, as indicated at b^2 in Fig. 7, after knitting the narrow high spliced portion b' in 115 the manner hereinbefore described. To accomplish this, I preferably provide a third thread guide as indicated at 12 in Fig. 2, which is normally out of operative position, and which carries a reinforcing thread 12^a 120 which may be of the same character as the reinforcing thread 10^a or of a different character as preferred, and after the narrow high spliced portion b' has been knit, the threaded guide 10 is thrown out of operative position, as indicated in dotted lines 10^b in Fig. 2, and the thread guide 12 is thrown into operative position as indicated at 12^b, Fig. 2, the said thread guide being so constructed as to deliver the reinforcing 130

thread 12^a below the plane of the hooks of the fashioning needles when the latter are in their highest or raised positions, as indicated in Fig. 2 so that the secondary reinforcing thread 12^a will be thereafter fed to all of the needles of the series knitting the rear portion of the stocking, which will therefore knit a plurality of courses, indicated at b² in Fig. 7 forming the lower part 10 of the high splice, and being of the same width as the first course of the heel pocket. I prefer to mount the thread guides 10 and 12 pivotally in a well known way so that they may be readily swung into and out of operative position, and this may be accomplished either by hand or by suitable connections from the pattern mechanism of the machine, as preferred.

I have not shown or described the specific mechanism for throwing the thread guides 20 10 and 12 respectively into and out of operation, as such means for actuating thread guides is known in the art, and one form of such mechanism is shown for example in Letters Patent of the United States No. 2. 669,730, granted to Edward E. Kilbourn, March 12th 1901. For the purposes of the present invention such mechanism for example may be employed or the thread guides 30 may be manipulated by hand.

While I have shown my invention as applied to a knitting machine of the Kilbourn type, I do not limit it to this type of machine, as in other types of circular knitting machines the same result might be obtained by providing a plurality of the needles knitting the back portion of the stocking with long nibs and lifting the same by means of a leading cam in advance of the knitting cam 35 so that the reinforcing thread can be fed thereto above the plane of the remaining needles knitting the back portion of the stocking.

What I claim and desire to secure by Letters Patent is:—

1. In a circular stocking knitting machine, the combination with a circular series of needles, stitch forming cam mechanism for actuating the same during circular and reciprocating work, and narrowing and widening mechanism, of means for feeding a reinforcing thread during circular work to a plurality of consecutive needles only, disposed substantially centrally of the group 50 of needles which knit the back of the leg, the sole, heel, and toe pockets, and being considerably less in number than the number of needles in said group, and means for feeding a reinforcing thread to a larger number of needles of said group, including the aforesaid consecutive needles and additional needles located on opposite sides thereof, whereby a narrow high spliced portion is formed at the back of the leg and a 55 number of reinforced courses of greater

length are formed between the narrow high spliced portion and the heel pocket.

2. In a circular stocking knitting machine, the combination with a circular series of needles, stitch forming cam mechanism 70 for actuating the same during circular and reciprocating work, and narrowing and widening mechanism, of a thread guide movable into and out of operative position for feeding a reinforcing thread during circular work to a plurality of consecutive needles only, disposed substantially centrally of the group of needles which knit the back of the leg, the sole, heel, and toe 75 pockets, and being considerably less in number than the number of needles in said group, and a separate thread guide movable into and out of operative position for feeding a separate reinforcing thread to a larger 80 number of needles of said group including the aforesaid consecutive needles and additional needles located on opposite sides thereof, whereby a narrow high spliced portion is formed at the back of the leg, and a number of reinforced courses of greater 85 length are formed between the narrow high spliced portion of the heel pocket.

3. In a circular stocking knitting machine, the combination with a circular series of needles, stitch forming cam mechanism 90 for actuating the same during circular work and reciprocating work, and narrowing and widening mechanism, of means for elevating a plurality of consecutive needles disposed substantially centrally of the group 95 of needles which knit the back of the leg, the sole, and heel and toe pockets to a greater extent than the needles of said group on either side of said centrally disposed consecutive needles, said consecutive needles 100 being considerably less in number than said group, and an auxiliary thread guide for feeding, during circular work, a reinforcing thread to said consecutive needles when elevated, at a point above the hooks of the remaining needles of said group. 110

4. In a circular stocking knitting machine, the combination with a circular series of needles, stitch forming cam mechanism for actuating the same during circular and reciprocating work, and narrowing and widening mechanism, a plurality of consecutive needles, disposed substantially centrally of the group of needles knitting the back of the leg, sole, and heel and toe pockets, and considerably less in number than said group, being provided with longer cam engaging nibs than the needles of said group at either side thereof, an auxiliary cam in advance of the knitting cam mechanism for said group of needles, constructed to engage said longer nibs and elevate the said consecutive needles so provided, above the plane of the adjacent needles of the said group, a main thread guide for delivering the main 120 125 130

knitting thread to all of the needles of the circular series during circular work, and an auxiliary thread guide for delivering a reinforcing thread to said consecutive 5 needles only, when in elevated position, and at a point above the hooks of the other needles of said group.

5. In a circular stocking knitting machine, the combination with a circular series 10 of needles, stitch forming cam mechanism for actuating the same during circular and reciprocating work, and narrowing and widening mechanism, of means for elevating a plurality of consecutive needles of the 15 group of needles knitting the back of the leg, sole, and heel and toe pockets, said consecutive needles being located centrally of said group and being considerably less in number than said group, a main thread 20 guide for feeding a main knitting thread during circular work to all of the needles of the circular series, an auxiliary thread guide operable during circular work and movable into and out of operative position, 25 for feeding a reinforcing thread to said consecutive needle only, when in elevated position, at a point above the hooks of the remaining needles of said group, and a second auxiliary thread guide operable during 30 circular work and movable into and out of operative position, for delivering a reinforcing thread to a larger number of the needles of said group including said consecutive needles, whereby a narrow high 35 spliced portion of less width than the longest course of the heel pocket may be formed at the back of the leg above the heel, and a number of longer reinforced courses may be formed between said narrow high spliced 40 portion and the heel pocket.

6. In a circular stocking knitting machine, the combination with a circular series of 45 needles, stitch forming cam mechanism for actuating the same during circular and reciprocating work, and narrowing and widening mechanism, of means for elevating a plurality of consecutive needles of the group of needles which knit the back of the leg, sole, and heel and toe pockets, above the 50 needles of said group at either side of said consecutive needles, the said consecutive needles being located centrally of and being considerably less in number than said group, means operable during circular work for 55 feeding a main knitting thread to all of the needles of the circular series, means operable during circular work for feeding a splicing thread to said consecutive needles when in elevated position at a point above the hooks 60 of the other needles of said group to form a narrow high splice, and means operable during reciprocating work for feeding all the thread composing the heel and toe pockets to the needles of said group at a 65 point below the hooks of the needles at

either side of said centrally located consecutive series of needles, whereby it will be taken by all of the needles operated, in each course of the heel.

7. In a circular stocking knitting machine, 70 the combination with a circular series of needles, stitch forming cam mechanism for actuating the same during circular and reciprocating work, and narrowing and widening mechanism, of means for elevating a plurality of successive needles of the group 75 of needles knitting the back of the leg, sole, and heel and toe pockets, and located substantially centrally between the fashioning needles above the adjacent needles at either 80 side of said consecutive needles, means for delivering a main knitting thread to all of the needles of the circular series, during circular work, means for delivering a reinforcing thread to said centrally located consecutive 85 non-fashioning needles when in elevated position at a point above the hooks of the fashioning needles, means operable during circular work for delivering a reinforcing thread to a number of consecutive needles 90 of said group at a point below the position of the fashioning needles, and means operable during reciprocating work for feeding the thread composing the heel to all the needles of said group at a point below the 95 hooks of the fashioning needles.

8. In a circular knitting machine, the combination with a circular series of needles, including a portion for knitting the front of the leg of the stocking and top of the 100 foot, and a portion for knitting the back of the leg and sole and the heel and toe pockets, of a cam cylinder operable during circular work and having a knitting cam for actuating the series of needles for knitting the 105 front of the stocking, a second cam cylinder provided with a knitting cam for actuating the needles knitting the rear portion of the stocking during circular and reciprocating work, a plurality of the needles located between the fashioning needles being provided with longer nibs than the needles at either 110 side of the same, said second cam cylinder being provided with a leading cam in advance of the knitting cam for raising the 115 needles having the said longer nibs, an auxiliary thread guide for delivering a reinforcing thread to said longer nib needles, when in raised position, above the plane of the hooks of the needles at either side of the 120 same, and capable of being moved into and out of operative position, and a second auxiliary thread guide capable of being moved into and out of operative position for feeding a reinforcing thread to all of the needles 125 actuated by said last mentioned knitting cam, below the plane of the hooks of the fashioning needles when the latter are in raised position.

9. In a circular knitting machine, the 130

- combination with a circular series of needles comprising a group of needles for knitting the front of the leg and top of the foot, and a second group of needles for knitting the 5 back of the leg and the heel and toe pockets, said group of needles comprising laterally disposed fashioning needles, and a centrally disposed series of non-fashioning needles, stitch forming cam mechanism for actuating 10 all of the needles during circular work and for actuating the said second group of needles only during reciprocating work, and narrowing and widening, or means operable during circular work for feeding a reinforcing thread to a plurality of consecutive 15 needles of the fashioning needles only of said second group of needles, for forming a narrow high splice at the back of the leg of the stocking.

10 10. In a circular knitting machine, the combination with a circular series of needles comprising a group of needles for knitting the front of the leg and top of the foot, and a second group of needles for knitting 20 the back of the leg and the heel and toe pockets, said second group of needles comprising laterally disposed fashioning needles, and a centrally disposed series of non-fashioning needles, stitch forming cam mechanism for actuating all of the needles during circular work and for actuating the said second group of needles only during reciprocating work, and narrowing and widening, mechanism operable during circular work for elevating a plurality of consecutive needles of 25 said non-fashioning needles during each course to a greater extent than the remaining needles of said group, a thread guide for feeding main knitting thread to all of said needles, at a point below the hooks of the fashioning needles, and an auxiliary thread guide for feeding a reinforcing thread to said consecutive non-fashioning needles when the latter are in elevated position, at a point 30 above the hooks of the fashioning needles.

25 In testimony whereof I affix my signature in the presence of two witnesses.
